UNITED STATES PATENT OFFICE.

JOSEPH S. OTT, OF CHICAGO, ILLINOIS.

DESIGN FOR A LOOP ANTENNA.

Application filed August 5, 1925. Serial No. 14,319. Term of patent 7 years.

To all whom it may concern:

Be it known that I, JOSEPH S. OTT, a citizen of the United States of America, residing at Chicago, county of Cook, State of Illinois, have invented a new, original, and ornamental Design for a Loop Antenna, of which the following is a specification, reference being had to the accompanying drawings, forming a part hereof.

Figure 1, is a front elevation of a loop antenna embodying my design.

Figure 2, is a side or edge elevation of my loop antenna of Figure 1.

I claim:

The ornamental design for a loop antenna, substantially as shown.

JOSEPH S. OTT.
